FIG. 2.

Patented Oct. 19, 1926.

1,604,008

UNITED STATES PATENT OFFICE.

JOHN ANDREW WILSON, OF SHOAL LAKE, MANITOBA, CANADA.

DEVICE FOR DISPLAYING MERCHANDISE.

Application filed February 14, 1923. Serial No. 619,041.

The present invention relates to advertising and display media, having reference particularly to an improved apparatus adapted for protectively containing and successively displaying a plurality of articles of manufacture.

The invention has for its objects the provision of an attractive and useful device of this character which automatically functions to visually display, in rotation, a large number and variety of articles in a relatively small space; which protects the articles from being handled and from the accumulation of dust; and which is simple in construction, durable and readily operable.

In carrying out my invention, I employ a housing or casing having a display window, a rotary carrier constituting a stage having a plurality of peripheral compartments adapted for successive registration back of said window, operating mechanism for coincidentally rotating said carrier and opening and closing said window, and a motor for actuating said operating mechanism, all as hereinafter fully described and specifically set forth in the appended claims.

In the accompanying drawings forming part of this specification, Figure 1 is a front elevation illustrating an example of my improved device:

Fig. 2 is a plan view, the top of the casing being removed; and

Fig. 3 is a cross sectional view taken on the line 3—3 of Fig. 2.

In the drawings, 1 indicates a square box or housing which is mounted on a base 2, and provided with a removable lid 3, a front window 3^a and a rear door 3^b.

Rotatably mounted on a vertical spindle 4, is the rotary carrier or stage, which embodies a circular disc 6 constituting a platform, a circular disc 7 located over the disc 6 and spaced therefrom by means of a plurality of radial partitions 8, which are connected at their respective inner edges by means of walls 9, thus producing a plurality of peripheral compartments 10, which are respectively open at the front and closed at the rear and sides.

The spindle 4 is journaled at its upper end in a horizontal shelf 5, fixed across the box 1, and at its lower end in a base 2 of said box.

Mounted on a standard 11, supported by the shelf 5, is an electric motor 12, which is

connected to the operating mechanism by means of a belt 13 passing over a pulley 14 mounted on the motor shaft 12^a, and a driving wheel 15 mounted on a vertical shaft 16, said shaft 16 having mounted thereon a pulley 17, forming one of a differential train of gear wheels 18, 19, 20, 21 and 22, the wheels 18 and 19 being mounted on a shaft 16^a, the wheels 20 and 21 on a shaft 16^b, and the wheel 22 on a shaft 16^c. Also mounted on the shaft 16^c is an eccentric cam-wheel 23, adapted for operating an oscillatory arm 24, which is swingingly mounted on a pivot 25 extending upwardly from the shelf 5, said arm 24 being provided with a pin 26 for peripheral engagement with the cam-wheel 23.

Swingingly mounted on the spindle 4 is a two-armed lever 27, the long arm 27^a of which is connected with the free end of the arm 24, by means of a connecting-rod 28, and the free end of the short arm 27^b of said lever being connected to one end of a contractile spring 29 which is secured at its other end to a fixed member 29^a, said spring having a normal tendency to swing said short arms 27^b in the direction of the arrow *a*, Fig. 2 of the drawings, and the long arm 27^a in the opposite direction, whereby frictional contact is maintained between the pin 26 and the periphery of the cam-wheel 23.

Extending from the free end of the long arm 27^a of the lever 27, is a rod 30 having an eye 30^a connected to one end of a cord 31, which passes over sheaves 32 and 33 and is connected at its other end with a sliding shutter 34 adapted for opening and closing the window 3^a.

Swingingly mounted on the under side of the long arm 27^a of the lever 27 is a U-shaped catch 35 which is loosely pivoted on studs 36 and normally bears, at its free end part, on the upper surface of the disc 7 of the carrier, said carrier being provided with a plurality of lugs 37, respectively provided with a cam-face 37^a on one side over which the catch 35 may ride when moved in one direction.

The device is further provided with suitably located electric lamps 38 for illuminating articles, as 39, and partitions 40 are provided at each side of the window 3^a for concentrating the lamp rays.

As a means for holding the carrier in set position, I provide a swingingly mounted

rod 41 which is provided with a curved part 41^a for engaging pairs of the lugs 37, said rod being maintained in yielding contact with said lugs by means of a helical spring 42.

In operation, the carrier is charged through the door 3^b with a plurality of articles to be exhibited through the window 3^a, and then the motor 12 is started, whereupon 10 rotary movement is transmitted to the cam-wheel 23 by means of the differential gearing which acts to slowly move the long arm 27^a of the lever 27 in the direction of the arrow *b* and gradually allow the shutter 34 15 to close by its own gravity, when the shutter is closed and the long arm 27^a will have reached the end of its stroke, the catch will be positioned in hooked engagement over the upright side of a lug 37, whereby the return 20 stroke of the long arm 27^a will rotate the carrier in the direction of the arrow *c*, and bring the next compartment 10 into position back of the window 3^a, and coincidentally lift the shutter 34, the operation being continued to successively bring the articles on 25 display into view behind said window until the motor is stopped.

While I have illustrated and described a fair example of my improved device, I do 30 not wish to be understood as confining myself to the specific construction and design of the elements shown, as under the spirit of my invention, I believe that I am entitled to employ such variations of detail as may fall 35 within the scope of the appended claims.

Having thus described my invention, what

I claim as new and desire to secure by Letters Patent, is:—

1. An apparatus for advertising and displaying articles of manufacture of the type 40 described comprising, in combination with a casing having an opening therein, a platform in the casing, a shutter for the opening and mechanism for operating the shutter and rotating the platform comprising a vertical and rotatable spindle, a differential chain of gear wheels on said spindle, an eccentric cam wheel on the spindle, a swingingly mounted arm provided with a pin adapted for peripheral engagement with the 50 cam wheel, a second spindle, a two-armed lever connected to said arm and spring actuating means for said lever whereby frictional contact is maintained by the swingingly mounted arm with the cam wheel and flexible means connecting the shutter to the swingingly mounted arm.

2. Shutter operating mechanism comprising, in combination with a rotary or stage-carrying shaft and an eccentric, a swingingly mounted arm and a swingingly mounted, two-armed lever, the swingingly mounted arm being designed, at one end, for peripheral engagement with the eccentric and at the other end to be connected to said double lever and means for flexibly connecting the double lever with the shutter.

Signed at village of Shoal Lake, in the Province of Manitoba, Canada, this 26th day of December, A. D., 1922.

JOHN ANDREW WILSON.
